UNITED STATES PATENT OFFICE

MARIE E. FROMERT, OF EAST ROCKAWAY, NEW YORK

POWDER PUFF OR DIP

Application filed March 14, 1931. Serial No. 522,698.

This invention relates to improvements in powder puffs or dips and the method of making the same.

The invention has more particular relation to improvements in puffs formed from fibrous material in such manner that the puff proper and a handle for grasping it are all part of the same material.

The object of the invention is to produce a powder puff or dip of fibrous material in such manner that the puff proper is fluffy and will pick up and dust powder upon the skin while a portion of the fibres is so restrained as to form a handle for the puff.

15 A further object of the invention is to produce a powder puff and its handle from fibrous material which has been previously dyed in its process of manufacture.

20 A further object is to produce a sanitary powder puff which is protected in the different stages of its manufacture until the final stage when its protecting covering is removed, when it is immediately placed within a container until used.

25 The invention also has other objects, all of which will be hereinafter more particularly set forth and claimed.

Figure 1 represents a perspective view of a roll of the fibrous material partly broken away, which constitutes the first stage of the process for manufacturing the puffs.

Figure 2 represents a similar view after the outer sanitary transparent protecting coating has been applied to the roll.

30 Figure 3 represents a perspective view of a section cut from the roll, for one puff.

Figure 4 represents a detailed perspective view of the operator removing the protecting sanitary cover from the fibrous material, and

35 Figure 5 represents a perspective view of a finished puff or dip.

Described in general terms the method of producing the improved powder puff is as follows:

40 The cotton, wool or other fibres are first rolled tightly into a long roll as shown in Fig. 1. This roll is then dipped into a suitable dye, preferably dyes of the pastel shades, so that the dyes will extend entirely through the roll. The roll, as shown in Fig. 2, is then

coated on its exterior by dipping or brushing with a flexible translucent material that is sufficiently transparent to disclose the dye fibres within it. The roll is now cut into the proper lengths as shown in Fig. 3. The rolls are now packed into suitable receptacles and are ready for the process of producing the puff.

Up to this point and during the handling of the roll, it will be observed that the outer translucent coating 3, has protected the cotton or fibres and prevented them picking up dirt, bacteria or any other substance injurious to the skin.

When the rolls are finally ready for the production of the puff, the portion that is to constitute the handle 2 is grasped in the left hand, and the operator with his fingers removes the part 2 along the line 4-4, as shown in Fig. 4, and thus uncovers the cotton 5, which immediately seeks to expand as shown in Fig. 4.

After the translucent cover 2 is removed along the line 4, the puff is spread out by the fingers into the form shown in Fig. 5. This is readily accomplished because the roll has been previously compressed and when the restraint of the translucent material 2 is removed, it immediately expands. The translucent material for this reason performs two functions.

It protects the puff proper from contamination from handling, and holds the handle portion in its compressed and semi-rigid condition to allow the exposed puff portion to be fluffed out into a large soft fibre puff, which may be used to take up powder and dust it on the skin. When the fibres 5 are spread out to form the puff as in Fig. 5, the fibres, having been previously dyed with a harmless dye, assume a very beautiful and soft effect in color, and this color is the same as the handle, as the dye, in the compressed fibres of the handle 6, may be seen through the translucent material.

Just as soon as the process reaches this stage, the puffs are immediately placed in a container having a cellophane end through which they may be seen, but which is immediately closed to keep them from any contamination, and retain them in their sanitary con-

dition. The compressed fibres within the handle 6 are rigid enough so that this handle may be grasped by the fingers and the puff used to apply powder or the like without the fingers becoming smeared with the powder or color being applied.

As the dyes used are mostly pastel shades, the effect of these puffs in pinks, blues and lavenders, when finished, is very attractive.

10 The puffs, by the above method of cheap manufacture, are not only beautiful to look at, but are so constructed that a rigid handle is provided which is part of the puff and may be thrown away with the puff after being used 15 once.

15 A cheap article of manufacture of beautiful appearance and one that may be thrown away after once being used is thus produced, and in a manner that is thoroughly sanitary.

20 When the translucent material 2 that covers the puff proper, is pulled back as shown in Fig. 4, it is entirely removed along the line 4, so that the fibres of the puff may be spread in all directions to produce a symmetrical and 25 round flat puff as shown in Fig. 5.

Having thus described my invention, what I claim as new and desire to secure by Letters Patent is:

1. The method of manufacturing powder 30 puffs consisting in rolling fibrous material into compressed rolls, coating these rolls with translucent material, removing a part of the translucent material to leave a handle, and fluffing the fibrous material out where the 35 protector has been removed.

2. The method of making powder puffs comprising rolling a fibrous material into long rolls, dyeing these rolls a suitable color, coating the rolls with a translucent material, 40 dividing the rolls into proper sections, removing a portion of each section of translucent material to leave a handle for each puff, and fluffing out the fibrous material which was previously covered by the translucent material removed.

45 3. The method of making powder puffs, which consists in rolling cotton into compressed rolls, coating the rolls with an outer binding material, removing a portion of this 50 binding material on each roll to leave a handle, and finally fluffing out the cotton to form the puff where the binding material is removed.

4. A powder puff comprising a roll of compressed cotton fluffed out at one end and a flexible binding material on the compressed end to form a handle.

5. A powder puff comprising dyed cotton fibres in a compressed roll and fluffed out into 55 a puff at one end, and a transparent binding material over the compressed end of the roll to form a handle and show the cotton within.

In testimony whereof I affix my signature.
MRS. MARIE E. FROMERT.
